[57] **CLAIM**

The ornamental design for a blade for scissor, as shown and described.

DESCRIPTION

FIG. 1 is a left side elevational view of a scissor blade showing our new design, and further showing a second, coupled scissor blade and handle fragment in phantom illustration;

FIG. 2 is a top plan view of the scissor blade in the new design of FIG. 1 (omitting the phantom illustration therefrom);

FIG. 3 is a bottom plan view thereof;

FIG. 4 is a right side elevational view thereof;

FIG. 5 is a front elevational view thereof;

FIG. 6 is a sectional view along a plane indicated by line 6—6 in FIG. 1; and,

FIG. 7 is a sectional view along a plane indicated by line 7—7 in FIG. 1.

My new design for a blade for scissor is believed adequately shown in the above-discussed FIGS. 1-7 of the drawings.
